UNITED STATES PATENT OFFICE

CHARLES SHULMAN, OF NEW YORK, N. Y.

DESIGN FOR A TABLE LAMP BASE OR ARTICLE OF SIMILAR NATURE

Application filed November 25, 1930. Serial No. 37,784. Term of patent 3½ years.

To all whom it may concern:

Be it known that I, CHARLES SHULMAN, a citizen of the United States, residing in New York city, in the county of New York and State of New York, have invented a new, original, and ornamental Design for a Table Lamp Base or Article of Similar Nature, of which the following is a specification, reference being had to the accompanying drawings forming a part thereof.

Fig. 2 is another side elevational view thereof.

Fig. 3 is a perspective view thereof.

I claim:

The ornamental design for a table lamp base or article of similar nature, as shown.

In testimony whereof I affix my signature.

CHARLES SHULMAN.
